UNITED STATES PATENT OFFICE

RALPH N. ALDRICH, OF SAN FRANCISCO, CALIFORNIA, ASSIGNOR TO STANDARD STATIONS, INC., OF SAN FRANCISCO, CALIFORNIA, A CORPORATION OF DELAWARE

DESIGN FOR A COMBINED BUILDING COLUMN AND DISPLAY CASE

Application filed April 6, 1932. Serial No. 43,410. Term of patent 14 years.

To all whom it may concern:

Be it known that I, RALPH N. ALDRICH, a citizen of the United States of America, residing in the city and county of San Francisco, State of California, have invented a new, original, and ornamental Design for a Combined Building Column and Display Case, of which the following is a specification, reference being had to the accompanying drawing, forming part thereof.

In the drawing showing my new design, Figure 1 is a perspective view of a combined building column and display case and Figure 2 is a sectional view through the display case.

I claim:

The ornamental design for a combined building column and display case, as shown.

Signed at San Francisco, California, the 1st day of April, 1932.

RALPH N. ALDRICH.
